United States Patent Office.

WILLIAM A. BARLOW, OF ELKHORN, WISCONSIN.

Letters Patent No. 60,844, dated January 1, 1867.

HEATING STOVES.

The Schedule referred to in these Letters Patent and making part of the same.

TO ALL WHOM IT MAY CONCERN:

Be it known that I, WILLIAM A. BARLOW, of Elkhorn, in the county of Walworth, and State of Wisconsin, have invented an Improved Stove, which is specially applicable to burning bituminous coal, peat, &c.; and I do hereby declare that the following is a full and exact description thereof, reference being had to the accompanying drawings, making part of this specification—

Figure 1 being a top view of the stove, the cover or top plate being removed.

Figure 2, a central vertical section thereof in a plane indicated by the line $x\ x$, fig. 1.

Figure 3, a horizontal section of the same in a plane indicated by the line $x\ x$, fig. 1.

Like letters designate corresponding parts in all of the figures.

Let A represent the body of the stove. In the upper part thereof I insert two concentric, or nearly concentric cylinders, so as to form an outer annular chamber, B, a central chamber, C, and an intermediate annular chamber, G; and inside of the interior chamber C I place a downwardly projecting flue or pipe, D, substantially as shown. The outer chamber B is closed at the top, but at the bottom it is open, so as to communicate with the fire chamber below; and the draught first circulates upward therein. The products of combustion then pass from the upper part of the chamber B, through flue openings or pipes, $a\ a$, into the upper part of the chamber C, which is closed both at the top and bottom. The draught then, after plunging down nearly to the bottom of the said interior chamber, finally ascends through the pipe D to the smoke pipe E. The plunging movement of the draught in the chamber C causes the greater part of the soot and particles of unconsumed fuel to be deposited on the bottom, H, of the said chamber. This bottom is made to tilt, when desired, as indicated by red lines in fig. 2, or otherwise to open, so as to discharge the soot collected thereon down into the fire chamber to be at once consumed. The bottom H is then righted or closed again, and the operation of the stove goes on as before. The bottom is operated by a rod, m, extending up through the top of the stove, or by any other suitable means. This construction is peculiarly effectual in depositing the soot and products of imperfect combustion from the draught and preventing their escape into the chimney to foul it and the atmosphere above it, so that thereby bituminous coal may be burned with cleanliness. The intermediate annular chamber G, although not necessary to the device above set forth, is very useful as an addition thereto, in obtaining much heat from the stove which otherwise might be wasted in the draught. It also protects the partition plate or plates, between the chambers B and C, from burning out, by keeping comparatively cool air in contact with them. Air from the outside is admitted freely into this chamber G, through one or more pipes or passages $b\ b$, across the annular chamber B; and the upper end of this air chamber opens into the space under the cover I, which has perforations or openings, $f\ f$, by which the air escapes into the room after circulating through and becoming heated by the walls of the chamber. The pipes or passages $a\ a$, which form the communication between the chambers B and C, cross this air chamber and assist in heating the air therein. In connection with the inverted chamber B and the closed interior chamber C, I introduce air in small streams through apertures $d\ d$, under the bottom H of the said chamber C, against which the products arising from the burning fuel first impinge. Thus fresh air is supplied so as to complete the combustion quite perfectly and deposit considerable of the soot before the draught proceeds further upward. As represented regularly in the drawings, these apertures $d\ d$ open from the air chamber G, whence the air is drawn for supplying the combustion. But I contemplate a modified construction here, which may be preferable. An annular space or passage g , separated from the chamber G by a partition, p, (or applicable in place, if the chamber is not used,) is supplied from passages $i\ i$ formed through the chamber B. These passages are conveniently constructed by adding arc or segmental plates $l\ l$, under the pipes $b\ b$, so as to enclose crescent-shaped spaces between them. These additional plates also serve to protect the pipes $b\ b$ from destruction by the intense heat, and may be removable when requiring to be replaced. The partitions between the chambers B and C may be more or less conical, or otherwise vary from the cylindrical form represented. Stoves with the improvements specified above may have descending flues from the top to the base, and an ascending flue or flues from the base, without interfering with the operations or materially departing from the construction above described.

I do not claim an interior flue or smoke pipe, with a tilting bottom or damper, as I am aware that such have before been used; but what I claim as my invention, and desire to secure by Letters Patent, is—

The interior chamber C, provided with a tilting or otherwise opening bottom H, and a downwardly projecting pipe or flue D, substantially as and for the purpose herein specified.

I also claim the combination of the chamber C, constructed and arranged as above specified, and chamber B, substantially as and for the purpose herein set forth.

I also claim the combination of the air-circulating chamber G with the chambers B and C, constructed and arranged as above specified, substantially as and for the purpose herein specified.

I also claim the air-supplying openings or passages d d, at the base of the chamber C, constructed and arranged as above specified, substantially as and for the purpose herein set forth.

WM. A. BARLOW.
